UNITED STATES PATENT OFFICE.

STOCKTON BORTON, OF PHILADELPHIA, PENNSYLVANIA, AND CHARLES H. WILLCOX, OF NEW YORK, N. Y., ASSIGNEES TO THE WILLCOX & GIBBS SEWING MACHINE COMPANY, OF NEW YORK, N. Y.

ART OF MANUFACTURING HOSIERY.

SPECIFICATION forming part of Letters Patent No. 255,579, dated March 28, 1882.

Application filed April 4, 1881. (No model.)

To all whom it may concern:

Be it known that we, STOCKTON BORTON, of Philadelphia, in the State of Pennsylvania, and CHARLES HENRY WILLCOX, of New York city, county, and State, have invented a new and useful Improvement in the Art of Manufacturing Hosiery, which improvement is fully set forth in the following specification.

In the manufacture of hosiery the plan pursued with the best quality of goods has been to knit the several parts with selvage edges and unite them by an overseam. With goods of an inferior quality, commonly known as "cut hose," the expenditure of time and labor involved in this plan has been avoided by cutting the pieces from a sheet of knit material and stitching them together on a sewing machine. Ordinarily a chain-stitch machine is employed, and the seams, which are made with very long and rather loose stitches—say about seven to the inch—are formed at a considerable distance from the edges, partly because it is impracticable to sew very close to the raw edges of knit goods, but also and mainly to make a strong seam, not liable to be destroyed by raveling at the edges of the fabric. The margin thus left outside the seam is very objectionable and detracts from the value of the goods. To produce cut hose of a superior quality the pieces have been united by an overseam, either on a button-hole machine or on a machine making a zigzag lock-stitch, one stitch within the fabric and the next beyond the edge. They have also been united by a zigzag stitch entirely within the fabric, the edges being trimmed or cleared close to the outer row of stitches by a shearing attachment that operates simultaneously with the sewing mechanism, so as to trim the fabric as it is advanced by the feed of the machine. The button-hole and zigzag forms of stitch have been employed in order to prevent raveling, and also to enable a firm and sufficiently close seam to be produced. The mechanism for forming these stitches is necessarily slower in operation than that for forming a straight-ahead seam, and in the finished article the stitching is at a distance from the edge equal to or greater than the lateral movement of the fab-

ric or needle in sewing, and there is an appreciable ridge or welt.

In this invention a straight-ahead seam, preferably with a chain-stitch, which can be run with the greatest rapidity, is made, and as the pieces are sewed together the edges are mechanically cleared or trimmed by an attachment to the sewing machine, close to and parallel to the seam. The stitches are tight or well drawn up and short, about equal in length to the gage of the fabric—that is, to the distance from center to center of the knit loops—or not materially greater than said gage. Knit goods thus manufactured are superior in appearance and equal or superior in durability to those having the cut edges united by an overseam, or to the machine-cleared goods sewed with a zigzag stitch, and approximately equal to the so-called regular-made goods with selvage edges. By making the stitches about equal in length to the gage of the fabric they inclose only a few threads—say one or two corresponding threads on each of the two edges to be united—and being drawn tighter than could be done with a long stitch they hold the threads firmly, so that a margin is unnecessary to secure the permanence of the seam. The edges can therefore be trimmed as closely as possible to the seam, since so long as the stitches are not cut its strength is not seriously impaired. It is not necessary that the stitches should be exactly the gage of the fabric.

The seam may be made with the lock or other suitable form of stitch; but the chain-stitch is preferred, because it is elastic and is similar in its nature to the goods themselves, because the loops surround the knit threads after the fashion of a running noose, and thus bind them very tightly, and because the strength and regularity of the seam in itself are less affected than a lock-stitch by the formation of stitches in the interstices of the fabric without the interposition of the knit threads. The edges being closely trimmed, the seam has substantially the thickness of the rest of the article, and there is not the objectionable ridge or welt formed in the ordinary cut hose. The character of the seam, due to its being straight ahead and to the use of stitches not materially greater

than the gage of the fabric, in connection with the regular and close trimming of the edges, gives to the improved machine-cleared hosiery an appearance very different from anything 5 heretofore produced and renders it in quality superior to other cut hose.

The accompanying drawings, which form a part of this specification, illustrate the seam made in accordance with this invention, Figure 1 being a side view, and Fig. 2 a cross-section. In Fig. 1 the fabric is shown enlarged, and the threads are represented by plain lines in order that they may be clearly distinguished. A chain-stitch seam is shown. The knit fabric is represented by *a* and the seam by *b*.

In manufacturing the improved hosiery the well-known Willcox & Gibbs sewing-machine, which uses a single thread and makes a chain-stitch by means of a revolving hook or looper, 20 is employed, and preferably the automatic machine provided with an automatic or intermittent tension; but any of the ordinary forms of lock-stitch machines which complete each stitch independently can be used.

25 A shearing attachment or trimmer of any suitable construction can be used to trim or clear the edges of the goods; but the trimmer described in an application for Letters Patent made by us and filed October 14, 1880, is considered best adapted to the purpose.

The size of the thread and needles will of course be adapted to the particular character of the fabric to be sewed, as is well understood by operators skilled in using the Willcox & 35 Gibbs machine, and the feed and other parts of the machine requiring adjustment will also be regulated according to the circumstances of the case.

The invention is not limited to hosiery proper—that is, stockings or socks—but includes 40 shirts, drawers, and other articles of wearing-apparel and knit goods generally.

By a "straight-ahead seam," as used in the specification, is to be understood a seam, whether curvilinear or straight, formed by a 45 series of stitches following each other in substantially the same direction, in contradistinction to a seam in which the stitches alternately deviate from the general direction of the seam and make what is known as a "zigzag stitch." 50

We claim—

1. The improvement in the art of manufacturing hosiery consisting in sewing the seam or seams with straight-ahead stitches equal or approximately equal in length to the gage of 55 the fabric, substantially as described.

2. The method of uniting hosiery so as to form with rapidity and economy strong closely-trimmed seams by running on a sewing-machine straight-ahead seams of stitches equal 60 or approximately equal in length to the gage of the fabric, and simultaneously with the sewing operation trimming off the excess of material beyond the seam in a continuous manner, substantially as described. 65

In testimony whereof we have signed this specification in the presence of two subscribing witnesses.
